VINCENTE SZAMIER, OF TERRYVILLE, CONNECTICUT.

SAFETY-LAMP.

Specification of Letters Patent.

Patented Aug. 3, 1915.

1,148,636.

Application filed April 15, 1914. Serial No. 831,982.

To all whom it may concern:

Be it known that I, VINCENTE SZAMIER, a citizen of the United States, and a resident of Terryville, in the county of Litchfield and State of Connecticut, have invented certain new and useful Improvements in Safety-Lamps, which improvements are fully set forth in the following specification.

This invention relates to improvements in fluid-burning lamps, and more particularly fluid-burning lamps of that class capable, each of extinguishing its own flame, upon being upset, the same being commonly known as safety lamps; and its object is to provide a lamp, lantern, or the like, of the character above indicated, which shall be simple and comparatively inexpensive as regards its construction; durable, efficient and reliable in practical service; which shall embody features of construction whereby is insured, in the event of the same being upset, particularly upon any object supporting it, the extinction, automatically, of the flame thereof; and which shall possess certain well-defined advantages over prior analogous constructions.

The invention consists in the combinations, details and parts whereby, together with the novel disposition and relative arrangement of said parts, the attainment of the foregoing object is rendered practical, all of which will be hereinafter more specifically referred to and set forth in the appended claims.

The invention is clearly illustrated in the accompanying drawings, wherein similar reference-characters denote like parts throughout the respective views, and Figure 1 is a fragmentary side elevation, partly in section, of a lamp embodying my said improvements. Fig. 2 is a fragmentary plan view of same, the trip-mechanism housing being removed, and the guard for the trip-mechanism jaws being partially broken away. Fig. 3 is a view showing in side elevation and detached the wick-casing, certain parts immediately coöoperating therewith being shown in vertical section. Fig. 4 is a view showing in perspective and detached, the trip-mechanism which I purpose making use of, together with certain parts provided for co-operation therewith, the scale being somewhat enlarged.

Having reference to the accompanying drawings, 2 denotes an oil font, as of a lamp, lantern, or the like, the same being

provided with a burner 2', in the usual manner, said burner fitted with the usual upstanding wick-casing 2'', upwardly and downwardly on which rides a flame-extinguisher. This flame-extinguisher comprises, in this instance, a flattened sleeve 3, slidably surrounding the casing 2'', and having a downwardly extending arm 3', there being mounted on said sleeve, for a rocking action, as at the opposite points 4, 4', an upwardly extending flap 4'', an elastic element 5, preferably in the form of a leaf-spring and attached to the sleeve 3, as by means of rivets 5, or other suitable fasteners, being provided for controlling the flap aforesaid. The spring 5 bears, at its free end, against the obverse face of the flap 4'', and tends at all times to rock and cause the same to normally span and close the top of the sleeve 3, said flap effectively assuming this sleeve-closing position when said sleeve duly approaches and reaches its upper limit of travel along the casing 3, and being engaged and rocked out of such sleeve-closing position, by the upper edge of the adjacent wall of said casing, when said sleeve is caused to slide an appropriate distance downwardly along such casing, all as will be readily understood, the construction thus far described being common and well-known in the art.

6 is an operating lever, pivotally disposed as at the point 6', said lever extending from a point exteriorly of the burner 2', freely through the wall of said burner, by way of a suitable opening 6'' formed therein, to a point interiorly of the burner, alongside the wick-casing 2, and into a loose engagement with the arm 3', depending from the sleeve 3, the adjacent end-portion of said lever, 95 freely entering, by preference and in this connection, an eye 7, formed in the arm 3', as clearly shown in Fig. 3.

A suitable elastic controller, as the extensible spiral spring 7', is interposed between the lever 6, in advance of its fulcrum 6', and any suitable fixed part thereunder, as the base 7'' of the burner 2', the tendency of said controller being, at all times, to thrust upwardly that portion of the lever 100 6 lying thereover, thus causing, through the medium of the arm 3' and in unison with such upward thrust of said lever, a like upward movement on the part of the sleeve 3, along the casing 2'', this movement on the 110 part of said sleeve being sufficient to bring the flap 4'' more or less upwardly beyond

- the top edge of the adjacent wall of the casing aforesaid, and so permit said flap to duly rock, under the impulse of its controlling spring 5, into the position the same 5 occupies, and as shown in Fig. 3, for closing the top of the sleeve aforesaid. It will be understood that when the flap 4" occupies its last-named position, as it fully does when sleeve 3 shall have been caused 10 or permitted to reach its limit of travel upwardly along the casing 2", air-circulation proper for the maintenance of the flame, as customarily induced at the top of the wick 8 and the top of said casing, is effectively 15 checked, whereby said flame is extinguished.
- For steadyng the controller aforesaid, when taking the form of a spiral spring, an upstanding pin 8', fixed at its lower end, as to the base 7" of the burner 2', may be 20 disposed to rise axially within the convolutions of said controller, said pin terminating somewhat short of that portion of the lever 6, lying thereover, when the same occupies its lowermost position; and where the burner 25 2' is provided with an interior crown-plate, as 8", the latter may be suitably cut away, as clearly indicated in Fig. 2, to provide suitable clearance for that portion of the lever 6 which lies within the burner 2'.
- 30 The operating-lever aforesaid is provided, exteriorly of the burner 2', with a finger-piece 9, and also with a depending stem 9'. Said stem supports at its lower end a clevis 9", adapted to swing, as on the 35 horizontal pivot 10, somewhat upwardly and downwardly, said clevis, in turn, supporting a tongue 9'", adapted to swing, as on the normally upright pivot 10', somewhat laterally with respect thereto. As here shown, 40 the shank of the tongue 9''' occupies the space between the constituent, opposite, and in this instance, upward and lower, jaw-like members of the clevis 9", tongue 9''' being provided, specifically at its shank, 45 with a lateral detent 10", which serves to limit its aforesaid lateral movement, by being caused thereby to impinge against the adjacent portion, as 11, of the body of said clevis. Tongue 9''' is further provided with 50 a detent-shoulder 11', here shown as located at one side thereof, and its free-end portion, from and in advance of said detent-shoulder, appropriately diminishes, widthwise in this instance, to its tip.
- 55 There is attached, as by means of rivets 12, 12', to the burner 2', exteriorly thereof and beneath and in line with the exposed portion of the lever 6, a horizontal platform 12", on which is disposed a jaw 13, which jaw works 60 on a pivot 13'. Jaw 13 is elastically controlled by a suitable spring, as 13", which exerts thereon a force adapted to yieldingly hold the same normally against a suitable stop, as 14, and suitably in alinement lengthwise with the tongue 9''', said jaw being

provided, at its free-end portion with a detent-catch 14'. The disposition of the jaw 13 relatively to the tongue 9''' is such that, upon lever 6 being rocked on its fulcrum 6', against the action of its controlling spring 7', said tongue will move endwise in the direction of said jaw, and a distance sufficient to insure an interlocking engagement of the detent-catch 14' with the detent-shoulder 11', all coöperating parts of the device thus far described being accordingly locked and restrained against reverse action, as under the impulse of the spring 7', until duly released, as will be hereinafter explained.

It will be understood that a duplicate of the jaw 13, as 14'', arranged for action reversely to the action of the jaw 13, working on a pivot 15, corresponding to 13', and having a detent-catch 15', corresponding to 14', may be availed of when deemed advisable, the tongue 9''', in this latter instance, having an additional detent-shoulder 15'', corresponding to 11', and likewise an additional detent 16, corresponding to 10''; also, the jaws 13, 14'' being, under such provision in duplicate of the parts, controlled jointly, as through the medium of the spring 13' aforesaid, and in such a manner that each thereof is urged elastically at all times in the direction of the other, and normally against the stop 14, situated between them, and said spring, in this latter instance, being contractile and formed from flat material, bowed around said jaws jointly, at the heels thereof, and elastically contracting against the same, respectively, at its opposite ends. Again, where jaws in duplicate, as above specified, are availed of, tongue 9''', under proper manipulation of the lever 6, will move as hereinbefore explained, and to such an extent as will permit the opposite detent-catches 14', 15', to interlockingly engage, respectively, the opposite detent-shoulders 11', 15'', of said tongue, with the result, as to restraint on the parts, also as hereinbefore specified, of said jaw or jaws elastically yielding sufficiently, against the controlling spring thereof, to permit the foregoing endwise movement on the part of said tongue. A guard 16', overlying crosswise the jaw or 115 jaws aforesaid, in advance of the axis or axes of movement thereof, may be availed of when desired, but same is not materially important.

The elastically controlled jaw or jaws 120 aforesaid and parts more or less immediately coöperating therewith, constitute trip-mechanism which I purpose interposing between the lever 6 and an operating annulus 16'', the latter surrounding the oil-font 2 125 and being free to move independently thereof and in all directions radially with respect thereto, as under a concussion or force correspondingly applied thereto at any point therealong, said annulus being yieldingly 130

suspended, at one side thereof, from the burner 2, as through the medium of a resilient arm 17, suitably connected at its lower end with said annulus, and connected, as by 5 means of a rivet 17', at its upper extremity, with the burner 2', a portion of said arm being returned thereunder, from its upper extremity, for the formation of a counterpoise branch 17'', whose lower, free end bears on 10 the oil-font 2, and which materially aids the arm 17 in operating to elastically maintain the annulus 16'' in its normal position relatively to said oil-font. The annulus 16'' is more or less yieldingly suspended at its 15 side opposite to the arm 17, through the medium of a supplemental, upstanding arm 18, whose upper portion 18', is suitably turned to overlie the jaw or jaws of the trip-mechanism aforesigned, said portion 18', of the 20 arm 18, having a depending stud 18'', whose lower end contacts, though shiftably, with the platform 12'', thereby enabling arm 18, with its portion 18', to duly support, as stated, the annulus 16'', at the side thereof 25 now under consideration.

The trip-mechanism aforesigned, including the portion 18' of the arm 18, is inclosed by a box-like cap or housing 19, which well fits the platform 12'', and may be fastened 30 thereon in any convenient and well-known manner. In this connection, however, I purpose providing said housing, whose end-wall adjacent to the arm 18 is duly cut away, as at 19', to provide clearance for the portion 35 18', with opposite, depending ears, 20, 20', at the lower edges of its opposite side-members, respectively, which ears extend somewhat below said platform, when the housing is in place thereon, said platform being 40 suitably notched or cut away at its opposite side margins to accommodate said ears, and further make use of a pin 20'', the latter being inserted through said ears jointly, and in a manner to extend transversely along 45 said platform at the under side thereof, said ears being each duly perforated to this end.

The stud 18'' stands normally in such relation to the jaw or jaws of the trip-mechanism aforesigned, as to compel movement 50 thereof, in opposition to the spring which controls the same, as under movement of the annulus 16'' radially in any direction out of its normal position, said stud being universally shiftable within proper limits along 55 the platform 12''.

The foregoing end may be obtained by providing either or each of the jaws aforesigned with a pocket, as 20'', which is measurably occupied at all times by the 60 stud 18'', and from which said stud may not escape without exerting on the jaw, or jaws having such pocket a force adapted to compel the same to duly move in the manner above defined.

65 Where opposite jaws, as 13, 14'', are used,

the stud 18'' stands shiftably between them, at and measurably within, at its opposite sides, the pocket aforesigned with which each of said jaws is provided, all as clearly indicated in the drawings.

70

For positively holding the operating parts of my improved lamp locked, as against the tendency of the spring 7', I provide a supplemental lock, which consists of axially alined sections 21, 21', supporting a medial section 21'', offset therefrom in parallelism therewith, said sections 21, 21', rotating in opposite bearings 22, 22', arranged posteriorly to the stem 9', and with which platform 12'', in this instance is provided, one 80 of the axially alined sections aforesigned, as 21', being provided with a finger-disk, 22''.

When the operating parts of the device are primarily locked against the action of the spring 7', as hereinbefore explained, the 85 same may be positively locked in this condition, by turning the finger-disk 22'' properly to cause the medial section 21'' to lie against, or in close proximity to, the stem 9', at the back thereof, and this irrespective 90 of any movement imparted to the annulus 16'', the function of the latter being thereby annulled; while by further turning said finger-disk properly to cause said medial section to duly recede from said stem, the 95 primarily locked parts may, as by due manipulation of the annulus 16'', be freed to respond to the action of spring 7'.

If my improved lamp is upset, as on a 100 table or other object supporting it, the parts being primarily locked, as through the medium of the jaw or jaws aforesigned engaging the tongue 9'', as hereinbefore explained and wick 8 affording a flame at its top, annulus 16'', by coming in contact with 105 such table or other support, will, under the concussion thus sustained thereby, be moved out of its normal position relatively to the oil-font 2, said operating parts will be released accordingly, and said flame will be 110 promptly extinguished. Or, if the user desires, at any time, to extinguish said flame, through releasement of the operating parts as above defined, it is only needful for him to duly manipulate the annulus 16'', accord- 115 ingly.

It will be seen that my improved safety lamp is well adapted for the purposes for which it is intended, and further that the same may be modified to a considerable extent, particularly as regards the specific character of the trip-mechanism made use of, and as regards various minor details of the general construction, without departing 120 from the scope of the claims hereto appended.

I claim:

1. In a lamp or the like having an oil-font, the combination with a wick-casing 130 having a flame-extinguishing device ar-

- ranged to slide thereon, of a pivotally disposed, spring-controlled operating lever, whereby said flame-extinguishing device may be actuated, a stem depending from 5 said lever and having a shouldered tongue pivotally attached thereto at its lower end, a spring-controlled, swinging jaw, for elastically engaging said tongue at the shoulder thereof, and whereby said lever is locked 10 against the stress of its controlling spring, a yieldingly disposed annulus, arranged concentric to said oil-font, and a connection between said annulus and said jaw, whereby the latter, under shifting of said annulus 15 radially in any direction out of its normal position, is caused to release its engagement with said tongue.
2. In a lamp or the like having an oil-font, the combination with a wick-casing 20 having a flame-extinguishing device arranged to slide thereon, of a pivotally disposed, spring-controlled, operating lever, whereby said flame-extinguishing device may be duly actuated, a stem depending from said lever and having a clevis pivotally attached thereto at its lower end, said clevis in turn having a shouldered tongue pivotally attached thereto, a spring-controlled, swinging jaw, for elastically engaging said 30 tongue at the shoulder thereof, and whereby said lever is locked against the stress of its controlling spring, a yieldingly disposed annulus, arranged concentric to said oil-font, and a connection between said annulus 35 and said jaw, whereby the latter, under shifting of said annulus radially in any direction out of its normal position, is caused to release its engagement with said tongue.
3. In a lamp or the like having an oil-font, the combination with a wick-casing 40 having a spring-controlled, flame-extinguishing device arranged to slide thereon, of a yieldingly disposed annulus, arranged concentric to said oil-font and carrying an upstanding arm, and trip-mechanism interposed between said flame-extinguishing device and said arm, and adapted to lock said flame-extinguishing device against the stress 45 of its controlling spring, said arm having a portion measurably overlying said trip-mechanism, and affording a stud co-operating therewith in a manner to cause the same,

under shifting of said annulus radially in any direction out of its normal position, to release said flame-extinguishing device for 55 response to the stress of its controlling spring.

4. In a lamp or the like having an oil-font, the combination with a wick-casing having a spring-controlled, flame-extinguishing device arranged to slide thereon, of a pivotally disposed, spring-controlled operating lever, whereby said flame-extinguishing device may be actuated, a stem depending from said lever and having an oppositely 65 shouldered tongue pivotally attached thereto at its lower end, opposite, spring-controlled jaws, for elastically engaging said tongue at the opposite shoulders thereof, respectively, and whereby said lever is locked 70 against the stress of its controlling spring, a yieldingly disposed annulus, arranged concentric to said oil-font, and a connection, the latter leading upwardly from said annulus and having a stud operating between 75 said jaws in a manner to cause the same, under shifting of said annulus radially in any direction out of its normal position, to jointly release said tongue, for response on the part of said lever to the stress of its controlling spring.

5. In a safety lamp or the like having an oil-font, the combination with a burner of a platform attached thereto at one side thereof, a counterpoise arm having a stud shiftably bearing downwardly on said platform, said counterpoise arm extending in a general downward direction from said platform, at one side of said oil-font, a returned, resilient arm, attached to said burner at the opposite side thereof, and extending in a general downward direction therefrom at the opposite side of said oil-font, and an annulus, the latter arranged concentric to said oil-font, and supported at one side thereof by said 85 counterpoise arm, at its lower end, and at the opposite side thereof, by one of the members of said returned arm, at its lower end, the other member of said returned arm, bearing at its lower end on said oil-font.

VINCENTE SZAMIER.
